United States Patent Office

Des. 203,720
Patented Feb. 8, 1966

203,720

AIRCRAFT

Harold L. Jarchow, Worthington, and Maurice E. King,
Gahanna, Ohio, assignors to North American Aviation,
Inc.

Filed Jan. 12, 1965, Ser. No. 83,398

Term of patent 14 years

(Cl. D71—1)

FIG. 1 is a plan view of the aircraft showing our new design;

FIG. 2 is a side elevational view thereof;

FIG. 3 is a front elevational view thereof;

FIG. 4 is a rear elevational view thereof; and

FIG. 5 is a perspective view of the aircraft in flight.
We claim:

The ornamental design for an aircraft, as shown.
